UNITED STATES PATENT OFFICE.

JOSEPH A. DUGAN, OF NEW ORLEANS, LOUISIANA.

MILK-BOTTLE CAP.

Application filed December 30, 1926. Serial No. 158,069.

The present invention relates to improvements in milk bottle closures and has for its primary object to provide a milk bottle cap having means for efficiently removing 5 the cap from the bottle.

A further object of the invention is the provision of a cap of the above character arranged to detachably engage a cap pulling member by means of which the cap may 10 be efficiently removed from the bottle opening.

Another object of the invention is the provision of a milk bottle cap carrying a pulling member arranged to withdraw the 15 cap without tearing or mutilating the same so that the cap may be repeatedly used as a closure.

Still another object of the invention is the provision of a milk bottle cap of the above 20 character which is simple and durable of construction and efficient for the purpose intended.

Other objects and advantages of the invention will become apparent as the description progresses.

In the accompanying drawing forming a part of this specification wherein like reference characters are employed to designate corresponding parts throughout the same:

30 Figure 1 is a top plan view of my improved cap shown in operative position as a closure for a milk bottle,

Figure 2 is a fragmentary sectional view taken on the line 2—2 of Figure 1,

35 Figure 3 is a top plan view of the cap with the pulling member removed, and

Figure 4 is a perspective view of the cap pulling member.

Referring to the drawing, wherein for the 40 purpose of illustration is shown the preferred embodiment of my invention, the numeral 10 generally designates a milk bottle cap of conventional construction adapted to be snugly fitted in the delivery opening of a milk bottle 11. In the construction of the cap for the present application, the cap member may be formed of paper or suitable material and is preferably waxed. Formed transversely in the center of the cap for engagement with a pulling member is an elongated slit 12.

The pulling member embodies a substantially T-shaped member 13 of relatively thin structure constructed of paper or other suitable material and comprises a rectangular elongated base strip 14 materially longer

in structure than the length of the slit 12 in the bottle cap, and a rightangular taper tongue 15 which is of greater width and shorter than the base strip. The tongue is 60 formed so as to be projected through the slit 12 and tightly fitted therein.

As clearly illustrated in Figures 1 and 2, the pulling member 13 is normally arranged in a substantially horizontal position lying against the cap. The tongue 15 projects through the slit 12 and is disposed on the top of the cap while the base strip 14 is arranged beneath the cap. When it is desirable to remove the bottle cap 10, the 70 tongue 15 is elevated to a vertical position, thereby arranging the pulling member in a straight vertical position with respect to the cap.

In this position, the base strip 14 will be arranged at right angles to the cap and the upper edge thereof will bear against the underside of the cap so that the cap may be removed without tearing or otherwise mutilating the same. An 75 essential feature of the construction is to

provide the pulling member with a relatively long base strip so as to extend substantially beyond the edges of the slit 12 to obviate the tearing of the pulling member or cap.

80 From the foregoing description and the drawing, it will be readily noted that the present invention provides a closure cap particularly adaptable for milk bottles and the like having a separable pulling member 85 designed to permit convenient and rapid removal of the closure cap without destroying the same so that the cap may be repeatedly employed as a closure member. This structure presents a cap which will be sanitary as well as convenient in use.

It is to be understood that the form of my invention herewith shown and described is to be taken as the preferred example of the same and that various changes as to the 90 shape, size and arrangement of parts may be resorted to without departing from the spirit of the invention or the scope of the subjoined claim.

Having thus described my invention, I 105 claim:

A bottle closure comprising a cap provided with a centrally located slit, and a pulling member embodying a base strip longer than the slit and occupying a position 110 substantially parallel to and in contact with the under side of the cap, the pulling mem-

ber also embodying a tongue of greater width and shorter than the base strip, the tongue extending through the slit and occupying a position substantially parallel to and contacting with the upper side of the cap, the base strip and tongue being arranged on opposite sides of the slit to permit the entire pulling member to be moved into

a right angularly related position with respect to the cap and with the upper edge of the base strip in contact with the under side of the cap. ¹⁰

In testimony whereof he affixes his signature.

JOSEPH A. DUGAN.
